(57) **CLAIM**

The ornamental design for a storage cabinet, as shown and described.

DESCRIPTION

FIG. 1 is a front elevation view of a storage cabinet showing my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a top, front, left side perspective view thereof;

FIG. 8 is a bottom, rear, right side perspective view thereof;

FIG. 9 is an enlarged view of detail "9" (identified in FIG. 7), shown at a greater scale for clarity of disclosure;

FIG. 10 is an enlarged view of detail "10" (identified in FIG. 8), shown at a greater scale for clarity of disclosure; and,

FIG. 11 is an enlarged view of detail "11" (identified in FIG. 8), shown at a greater scale for clarity of disclosure.

The broken lines shown in the drawings depict portions of the storage cabinet that form no part of the claimed design. The dash-dot broken lines represent boundaries of the enlarged portions and form no part of the claimed design.

1 Claim, 11 Drawing Sheets
